Inventor:

Edmund B. Wedmore,
by *Albert, Dan*
His Attorney.

UNITED STATES PATENT OFFICE.

EDMUND BASIL WEDMORE, OF GOLDER'S GREEN, ENGLAND, ASSIGNOR TO GENERAL ELECTRIC COMPANY, A CORPORATION OF NEW YORK.

ELECTRIC SWITCH.

Application filed April 14, 1920. Serial No. 373,910.

To all whom it may concern:

Be it known that I, EDMUND BASIL WEDMORE, a subject of the King of Great Britain, residing at 1 Sneath Avenue, Golder's Green, N.W., England, have invented certain new and useful Improvements in Electric Switches, of which the following is a specification.

My invention relates to improvements in electric switches, particularly to switches in which the contacts are separated under oil and which are provided with auxiliary or arcing contacts at which the circuit is broken after the main contacts have been separated.

The object of my invention is to provide a switch of the oil break type in which, as the contacts separate, oil is permitted to flow toward the arcing contact from all sides, and is directed into the arc path to assist in extinguishing the arc.

In switches of the oil break type, I have found that it is important that the oil surrounding the contacts should be allowed to flow freely towards the arcing contacts while the switch is opening. In switches as at present constructed, although the oil may flow freely towards the contacts from two or three sides, it is usually hindered by the cross-arm carrying the movable contact faces and by the attachment of the arcing contacts.

In accordance with my invention, I employ a construction of auxiliary or arcing contact and supporting means therefor which permits the oil to have free access to the contacts from all sides and a construction of main movable contact which, during the opening movement of the switch, causes the oil to flow towards the arcing contact so as to assist in extinguishing the arc.

The novel features which I believe to be characteristic of my invention will be definitely indicated in the claims appended here-to, while the features of construction and mode of operation will be understood by reference to the following description taken in connection with the accompanying drawing, in which examples of well known types of contacts commonly used prior to my invention are shown in Figs. 1 and 2, which are side and end elevations respectively of a well known type of moving contact for an oil break switch with its cooperating stationary

arcng contact and in Figs. 3 and 4 which are similar views of another well known type of contact structure; while some preferred embodiments of my invention are shown in the remaining figures of the drawing in which Figs. 5, 6 and 7 are side and end elevations and plan respectively of an arcing contact for an oil circuit breaker embodying the features of my invention; Fig. 8 is a side elevation similar to that of Fig. 5 showing the main brush contact and illustrating the path of the oil during opening of the switch; and Figs. 9, 10 and 11 are sectional side elevation, end elevation and plan respectively, of my improved structure of arcing and main contacts.

Figs. 1 and 2 show the main movable contact 1 and the movable arcing or auxiliary contact 2, which co-operate with the stationary arcing contact 3 of a circuit breaker. The main stationary contact is omitted for purposes of clearness. This is a well known form of contact structure for an oil break switch and it will be seen, that as the movable contacts are moved downwardly to open the circuit, the contact bar tends to force the oil to flow in a direction away from the arc formed between the stationary and movable arcing contacts.

In Figs. 3 and 4, another well known contact structure is illustrated. In this case, the main movable brush contact 4 and the auxiliary or arcing contact 5, both engage the fixed contact 6. Contact 5 is secured to contact 4 by means of a broad flat spring 7 and this again, during the opening movement of the switch, hinders the oil from flowing towards the arc formed at the arcing contact.

In Figs. 5 to 8, inclusive, I have shown my improved contact structure. In these figures, the arcing contact 8 is relatively wide, as best shown in Fig. 6; and is held between supporting bars 9 secured to the switch operating mechanism in any convenient manner. These bars 9 are made of thin or flat strips of metal mounted, as shown in Fig. 7, so as to move edgewise through the oil, thereby offering substantially no resistance to the flow of oil. Where this type of contact is used with a main contact of the brush type, as shown in Fig. 8, the bars 9 extend along each side of the main contact and the

curvature of the underside of the main contact is such that it tends to force or direct the oil towards the arc formed as the switch opens.

5 In Figs. 9 to 11, I have shown my improved arcing contact in combination with a cross-bar contact, the shape of which has been modified according to my invention. In these figures, is shown the arcing contact 8 and the strips 9 supporting it. The cross bar main contact 10 is curved on its underside, as will be seen from Fig. 9, so as to cause the oil to flow towards the arc formed at the arcing contact 8 when the switch is 15 opening.

In opening switches of this type, the movement of the oil would be relatively unimportant were it not that there is a tendency to develop a large body of gas in the 20 neighborhood of the arcing contact. If the oil is given an initial motion which tends to cause it to flow away from the arc, as in the case of switches as at present constructed, it will continue to move in the same direction 25 owing to the extension of the arc. If, however, the oil is caused to flow initially towards the arc, as is the case with my improved construction, it will distort the body of vapor carrying the arc and tend to 30 press it.

What I claim as new and desire to secure by Letters Patent of the United States, is:—

1. In an electric switch, the combination with stationary main and auxiliary contacts, 35 of movable main and auxiliary contacts cooperating with said stationary contacts and separable therefrom beneath an insulating liquid, said movable main and auxiliary contacts constructed and arranged to cooperate 40 to direct a flow of said liquid into the arc formed as said contacts separate and to permit free access of said liquid from all sides to said auxiliary contacts.

2. In an electric switch, the combination 45 with cooperating fixed and movable main contacts separable beneath an insulating liquid, cooperating fixed and movable auxiliary contacts separable beneath said liquid, and supporting means for said movable auxiliary contacts, said means being open below 50 said auxiliary contacts whereby free access is provided for the flow of insulating liquid into the arc path from all sides as the contacts separate.

55 3. In an electric switch, the combination with cooperating fixed and movable main contacts separable beneath an insulating liquid, cooperating fixed and movable auxiliary contacts separable within said liquid, 60 and supporting means for said movable auxiliary contact comprising metal bars secured

to each end of said auxiliary contact and movable edgewise through said liquid.

4. In an electric switch, the combination with cooperating fixed and movable main contacts separable beneath an insulating liquid, cooperating fixed and movable auxiliary contacts separable within said liquid, and flat metallic supporting bars secured to each end of said movable auxiliary contacts and movable edgewise through said liquid, said movable main contact being positioned between said supporting bars and shaped to cooperate with said auxiliary contact and said bars to direct a flow of said liquid into 75 the arc formed as said contacts separate.

5. In an electric switch, the combination with stationary main and auxiliary contacts within an insulating liquid, of a cooperating movable main contact-shaped to direct a flow of said liquid into the arc formed as said contacts separate, flat conducting bars extending beyond and on each side of said movable main contact arranged for edgewise movement through said fluid, and a cooperating movable auxiliary contact carried between the ends of said conducting bars there being permitted free access of said liquid to the arc path from all sides as the contacts 80 separate.

6. In an electric switch having cooperating fixed and movable main and auxiliary contacts separable under oil, said movable auxiliary contact consisting of relatively wide member mounted for edgewise movement through said oil, and flat metal supporting strips secured to each end of said movable auxiliary contact and movable edgewise through said oil, said movable main contact being mounted intermediate said 95 supporting strips and shaped to cooperate with said movable auxiliary contact to direct a flow of oil into the arc formed as said contacts separate.

7. In an electric switch, the combination 105 with stationary, main and auxiliary contacts within an insulating fluid, of a cooperating movable main contact shaped to direct a flow of said fluid into the arc formed as said contacts separate, flat conducting bars extending beyond and one each side of said movable main contact arranged for edgewise movement through said fluid, and a cooperating movable auxiliary contact carried between the ends of said conducting bars 110 and extending beyond the same toward said stationary auxiliary contact whereby free access of said fluid is permitted to the arc path from all sides as said contacts separate.

In witness whereof, I have hereunto set 120 my hand this 16th day of March, 1920.

EDMUND BASIL WEDMORE.
